ROTARY PUMP

Filed Oct. 5, 1923

UNITED STATES PATENT OFFICE.

OYSTEIN JACOBSEN, OF DAYTON, OHIO, ASSIGNOR TO THE DURIRON COMPANY, INC.,
A CORPORATION OF NEW YORK.

ROTARY PUMP.

Application filed October 5, 1923. Serial No. 666,694.

To all whom it may concern:

Be it known that I, OYSTEIN JACOBSEN, a citizen of the United States, and a resident of Dayton, in the county of Montgomery and State of Ohio, have made a new and useful invention in Improvements in Rotary Pumps, of which the following is a specification.

The invention relates to rotary pumps, and has for its principal objects, the provision of an improved pump, (1) which is of very simple design, having a minimum number of parts, (2) which is highly efficient and will remain so after a long period of wear, as the parts subject to the greatest wear are self adjusting to compensate for such wear, and (3) which is so constructed that the finishing or machine work on the parts is reduced to a minimum, rendering the pump particularly adaptable for construction from acid resisting material, such as high silicon iron, which is exceedingly hard. One embodiment of the invention is illustrated in the accompanying drawings wherein:

Figure 1 is a longitudinal section through the pump with mounting or base in side elevation. And Fig. 2 is a transverse section on the line II—II of Fig. 1.

Referring to the drawings, 1 is the base plate of the machine provided with three upstanding arms 2, 3 and 4 in which the shaft 5 of the pump is journaled. Mounted on the shaft is a pulley 6 by means of which the shaft is driven. Also carried by and secured to the shaft is the sleeve 5^a, and integral therewith is the rotor 7 of the pump, such rotor consisting of a disc which is eccentric with respect to the axis of the shaft.

The casing of the pump consists of the pair of opposing side plates 8 and 9 and the annular central member 10 clamped between the side plates by the bolts 11, such central member being provided with the base 12 (Fig. 2) secured to the base plate 1 by means of the stud bolts 13.

The side plates 8 and 9 are provided with the laterally extending stuffing boxes 14 and 15, carrying the packing 16 and having the follower members 17 and 18.

The central member 10 has its cavity concentric with the axis of the shaft 5 and is provided with the inlet or section passage 19 and the discharge or outlet passage

20. The wall of the central member is also provided with the transverse bearing cavities 21 and 22 extending entirely through the member to permit of the insertion of the lower ends 23 and 24 of the pawl shaped valve members 25 and 26 before the central member is clamped between the side plates 8 and 9. The valve members 25 and 26 yieldingly engage the periphery of the rotor 7 by reason of their weight, thus eliminating any requirement for springs. The arrow indicates the direction of rotation of the rotor, and the dotted lines (Fig. 2) show the position of the rotor and valve members when the rotor is at a position of rotation 180 degrees from that indicated in full lines.

In operation the water entering at the suction inlet 19 is carried around by the eccentric rotor in a counter clockwise direction and discharge through the outlet 20. The valve 26 automatically lifts to permit the passage of the water, and acts as a check valve to prevent any back flow from the outlet 20, since any back pressure acting upon the upper side of the valve member presses it against the periphery of the rotor. The valve 25 is always in contact with the rotor, due to the fact that the suction on the lower side of the valve and the pressure on its upper side combine to press it against the rotor. This prevents any leakage of liquid from the discharge outlet to the suction inlet during the operation of the pump, thus insuring a steady flow from the pump, and when the movement of the rotor is discontinued, the valve still acts to prevent any leakage back to the inlet.

It will be seen that the apparatus is of very simple construction, requiring a minimum amount of finishing work, which is a highly desirable condition when very hard acid resisting material, such as high silicon iron, is employed. The valve members 25 and 26 may be made of the same material as the body of the pump and require no finishing, except on the limited areas, which contact with the rotor, which surfaces are readily ground. The positioning of the valves so that they may be operated by gravity is advantageous as this avoids the complications and upkeep difficulties incident to the use of the springs, which would be particularly objectionable in a pump designed to handle corrosive liquids, in which the springs would either require protection

or frequent replacement. The method of pivoting the valves is simple and cheap. No refinishing of the parts at these points is required, the cavities 21 and 22 being cored out, and the parts are readily assembled before the side plates are bolted on. The wear between the valves and rotor does not affect the efficiency of the apparatus and such wear is very slight where hard acid resisting metal is used, so that the pump will run indefinitely without adjustment or repair. The use of the sleeve 5^a integral with the rotor and of the same acid resisting material gives protection to the shaft 5 against the liquid of the pump and permits the use of ordinary shafting which is more suitable for this purpose than is the composition from which the sleeve is made. Other advantages of the construction will be readily apparent to those skilled in the art.

What I claim is:

1. In combination in a rotary pump, a shaft with a rotor in the form of an eccentric disc carried thereby, a pump casing 25 having a chamber concentric with respect to the axis of the shaft in which the rotor is mounted, and having inlet and outlet passages leading through the walls of the chamber opposite the periphery of the rotor, and 30 a pair of gravity valves pivoted in the casing on opposite sides of the outlet passage and having their free ends in engagement with the periphery of the rotor throughout the rotation thereof, both of the valves being arranged to prevent a back flow of

liquid from the outlet passage around the periphery of the rotor, and the valve on the inlet side of the outlet passage being arranged to permit a forward flow of liquid past it to the outlet passage.

2. In combination in a rotary pump, a sleeve having a rotor integral therewith in the form of an eccentric disc, a shaft extending through the sleeve, a central annular casing member in which the rotor is mounted with the axis of the shaft concentric with the opening in the casing, and side plates through which the sleeve extends clamped to the opposite sides of the central casing member, the said central casing member being provided with an inlet passage and an outlet passage.

3. In combination in a rotary pump, a sleeve having a rotor integral therewith in the form of an eccentric disc, a shaft extending through the sleeve, a central annular casing member in which the rotor is mounted with the axis of the shaft concentric with the opening in the casing, and side plates through which the sleeve extends clamped to the opposite sides of the central casing member, the said central casing member being provided with an inlet passage and an outlet passage, and such member, the side plates, rotor and sleeve being of corrosion 60 resisting metal.

In testimony whereof, I have hereunto subscribed my name this third day of October, 1923.

O. JACOBSEN.
